DISPLAY SHELF

Ernest Frederick Thomson, North Salem, N. Y.,
assignor to The Globe-Wernicke Co., Norwood,
Ohio, a corporation of Ohio

Application March 29, 1950, Serial No. 8,837

Term of patent 14 years

(Cl. D80—9)

To all whom it may concern:

Be it known that I, Ernest Frederick Thomson, a citizen of Canada, residing at North Salem, in the county of Westchester and State of New York, have invented a certain new, original, and ornamental Design for Display Shelf, of which the following is a specification, reference being had to the accompanying drawing forming a part hereof.

Figure 1 is a top plan view of a display shelf, showing my new design.

Figure 2 is a front elevational view.

Figure 3 is a side elevational view.

Figure 4 is a cross sectional view thereof, taken on the line 4—4 of Figure 2, and

Figure 5 is a perspective view.

I claim:

The ornamental design for a display shelf, substantially as shown.

ERNEST FREDERICK THOMSON.
